UNITED STATES PATENT OFFICE.

CHARLES W. KINTER AND CHARLES H. MANION, OF FOLLANSBEE, WEST VIRGINIA,
ASSIGNORS TO FOLLANSBEE BROTHERS COMPANY, OF PITTSBURGH, PENNSYLVANIA, A CORPORATION OF PENNSYLVANIA.

PLATE REVERSING AND COOLING MECHANISM.

Application filed May 20, 1927. Serial No. 193,044.

This invention relates broadly to cooling conveyors for freshly coated metal plates, and it has for its primary object to provide a conveyor by means of which the plates are advanced following the coating operation for effecting cooling of the coating metal and whereby the plates are so handled as to prevent the deposit upon edges thereof of excess coating metal in the form of list.

10 A further object is to provide a cooling conveyor by means of which the freshly coated plates are automatically moved to reversed positions promptly following the coating operation, or while the coating metal 15 remains in fluid condition, for redistributing by gravity the surplus coating metal which would otherwise collect in the form of list upon the lower edges of the plates.

The elimination of list from coated metal 20 sheets is particularly desirable, because, when cooled, it constitutes a bead of such relatively great thickness that not only is the appearance of the sheet or plate marred thereby, but the later working of the plate is therefore interfered with, or rendered difficult. In 25 the present invention list elimination and handling of the sheets for effecting cooling are accomplished by one and the same mechanism.

30 In describing the invention in detail, reference is herein had to the accompanying drawings, in which—

Figure 1 is a side elevation of the invention;

35 Figure 2 is a top plan view of the same;

Figure 3 is a detail sectional view, enlarged, taken substantially on line 3—3, Fig. 2;

40 Figure 4 is an enlarged cross section of a chain-carried bar, showing the attaching lug;

Figure 5 is a face view of the circular motor-control switch;

Figure 6 is a section on line 6—6, Fig. 5; and—

45 Figure 7 is an enlarged side elevation, partly in section, of the limit switch.

Referring to said drawings, 1 designates the legs of a frame which supports at convenient height the side members 2 of a rectangular bed or table having transverse supporting members or bars 3 superposed thereon. Carried by said bars 3 are suitably disposed longitudinally extending trackways 4 upon which may travel the upper laps of con-

veyor chains or belts 5 that may embody friction-reducing rollers 6. Said chains 5 are carried by sprocket wheels 7 mounted on shafts 8 which are journaled in suitable bearings 9 mounted upon opposite ends of the frame members 2.

55 One of the shafts 8 is driven from the drive assembly, which, as herein shown, consists of an electric motor 10 and a gear-speed reduction unit 11, by means of an endless belt or chain 12 connecting sprocket wheels 13 and 14 carried, respectively, by the final driven shaft 31 of said drive assembly and by said shaft 8.

60 Carried by the conveyor chains 5 in suitably spaced relation are transverse carrier bars 15. The bar-attaching means herein shown, which is to be understood as illustrative only, comprises lugs 16 carried on the under sides of the bars 15 and attached to links of the chains by means of bolts or 65 pins 17.

65 Rigidly mounted on each of the bars 15 in suitably spaced parallel relation are the lower end portions of two upstanding metal fingers 18 designed as carriers for coated metal plates. Each of said fingers 18 has hook-like terminals 18^a and 18^b at its upper and lower ends within which are received the top and bottom edges, respectively, of the freshly 70 coated plates 19 as the latter, coming from the coating bath, are transferred thereto. Said fingers are rearwardly inclined relative to planes disposed at right angles to the conveyor chains and have their intermediate, or body, portions arcuately curved or bowed to the extent that the adjacent faces of the supported plates will not belly into contact therewith.

75 As each sheet comes from the exit rolls of the coating bath, it is immediately transferred, either manually or by appropriate mechanical means, to that pair of conveyor fingers 18 which occupies substantially the position shown at X in Fig. 1—that is, to the foremost pair of the returning fingers borne by the lower lap of the conveyor chains—said pair being then disposed in a downwardly and rearwardly inclined position. The lower edge of the plate so transferred, as the latter is entered in seating relation to said fingers, engages and depresses an end of a lever 20 which is pivotally mounted intermediate its end upon a suitable stationary support, as 80 85 90 95 100 105

21, located between the opposite sides of the rear end of the frame. Said lever constitutes the movable member of a switch, of limit-switch type, whereby an electric power circuit 5 to the motor 10 is closed for driving said motor. The opposite end of the lever 20 carries an electrical contact 22 which is located in one side of an electric circuit having a conductor wire 23 leading thereto from the source of 10 electrical energy. A contact 24 carried by the stationary member 26 of said switch, herein shown of bracket form, has a conductor wire 25 leading thereto from a terminal post (not shown) of said motor.

15 A motor control switch is provided at a suitable point, the purpose thereof being to continue the operation of the motor throughout a definite interval following the opening of the limit switch, hereinbefore described. 20 the movable member 20 of which is permitted to resume its normal position, actuated by a compression spring 27, instantly upon initiation of advance movement of the conveyor fingers from plate-receiving position.

25 Said control switch, as herein shown, comprises a circular disk 28 rigidly mounted upon the face of a boss 29 formed upon a bearing 30 in which is journaled an extension of the final driven shaft 31 of the drive assembly, 30 hereinbefore referred to. Said disk, as herein shown, is made of fiber or other material non-conductive of electric current and loosely embraces, or encircles, said shaft 31. Carried upon the outer face of said disk are two ring 35 segments 32 and 33 which are separated at diametrically opposite points by blocks 34 of non-conducting material and to each of which is connected a branch conductor 35 leading from the conductor 25 hereinbefore 40 referred to.

The projecting end, or extension, of the shaft, 31 has rigidly mounted thereon and insulated therefrom an arm 36 which, in the rotation of said shaft, travels in contact with 45 the faces of the segments 32 and 33 and the interposed blocks 34. The shaft embracing portion of said arm 36 carries a boss 36^a with which, in the rotation of said shaft, a spring contact 37, herein shown as mounted upon the motor bed 38, makes wiping contact. Said spring contact is connected by a branch conductor 39 to the conductor 23, hereinbefore referred to.

Starting of the motor, effected as hereinbefore described, by closing of the electric circuit through the limit switch upon seating a plate 19 in carrying position on the fingers 18 which occupy the receiving position shown at X in Fig. 1, serves to advance the conveyor 55 mechanism a short distance prior to the re-opening of said circuit which results from the elevation of said plate off the member 20 of said switch. In this short travel the arm 36 is rotated from the position in which it 60 rests upon the face of one of the insulator

blocks 34 into contact with the face of one of the ring segments 32 or 33, thus closing a branch circuit to the motor at about the same time that the main circuit through the limit switch is opened, causing the motor to continue its operation until the arm 36 passes from said ring segment to the next insulator block 34, whereupon the motor instantly stops. The distance traveled by the conveyor chains during the time that the arm 36 is being advanced from one insulator block 34 to the next is that which is required to advance the next in series of the pairs of carrying fingers of the conveyor to the plate-receiving position X.

70 The plate 19, which is mounted in the carrying fingers 18 at the receiving point X with its list-carrying edge down, is advanced to a reversed position in the short interval of time which elapses between the starting and stopping of the motor and which is the time required to advance the next succeeding set of fingers 18 to said receiving point, ready to receive the next plate. Thus, the surplus fluid coating metal which would otherwise solidify upon said edge of the plate is permitted to distribute promptly by gravity drainage over the surfaces of the plate.

75 In the further intermittent advance of the plate the coating metal becomes cooled. The plates are successively removed or discharged as they reach the front end of the conveyor frame, being either delivered in a pile or to a machine in which the next succeeding sheet-treating process is performed.

80 As used in the appended claims, it will be understood that the word "chains" is intended to embrace belts or other form of endless traveling members.

85 What is claimed is—

1. In a plate reversing and cooling mechanism, endless conveyor chains, a plurality of supporting members mounted on said chains in uniformly spaced relation, a pair of fingers constituting a plate carrier mounted on each supporting member in upstanding relation to the latter, each finger having at its opposite ends plate-edge-receiving terminals of hook-like form, and means for intermittently advancing said chains throughout the distance between successive plate carriers.

105 2. In a plate reversing and cooling mechanism, endless traveling chains, a plurality of plate carriers borne by said chains in uniformly spaced relation, each carrier comprising a supporting member and a plurality of fingers, said fingers having their lower end portions mounted in rigid relation to said member, each finger having at its opposite ends seats for the reception of opposite edges of a plate, and means for intermittently advancing said chains throughout the distance between successive carriers.

110 3. In a plate reversing and cooling mechanism, endless traveling chains, a plurality of

- plate carriers borne by said chains in uniformly spaced relation, each carrier comprising a suitable support and a pair of fingers, the latter having their lower end portions rigidly mounted on and occupying inclined upstanding relation to said support, each finger having at its opposite ends seats for the reception of opposite edges of a plate, and means for intermittently advancing said chains throughout the distance between successive carriers. 5
4. In a plate reversing and cooling mechanism, endless traveling chains, a plurality of plate carriers borne by said chains in uniformly spaced relation, an electric drive including a motor, and means for energizing said motor intermittently for advancing said chains throughout the distance between adjacent carriers for presenting the latter successively in plate-receiving position, which distance is also that required to effect reversal of the plate in its movement from said position, said energizing means including two electric power circuits to the motor, a normally open switch located in one circuit and adapted to be closed by the introduction of a plate in a carrier occupying receiving position and to open automatically upon a slight advance of said plate from said position, and
- a normally open switch located in the other circuit which is actuated to close upon starting of said drive mechanism for maintaining the motor energized throughout a definite interval of travel. 30
5. In a plate reversing and cooling conveyor, endless traveling chains, successive plate carriers borne by said chains in spaced relation, means including an electric motor for driving said chains, a normally open motor circuit including a shiftable contact member, said member being movable to circuit closing position by introduction of a plate in a carrier occupying receiving position and being adapted to return automatically to circuit opening position upon an initial advance of said carrier from said receiving position, a normally open motor control circuit, and means actuated in such initial advance whereby said control circuit is closed for continuing the advance of the carrier throughout the distance between successive carriers, said distance being predetermined to provide reversal of each plate in the movement of its carrier from said receiving position. 35
